AIR COOLED LEDGE PLATE FOR TRAVEL-
ING GRATE STOKERS

Elliott E. Smith, Scranton, Pa.

Application March 13, 1936, Serial No. 68,650

6 Claims. (Cl. 110—40)

This invention relates to new and useful improvements in a ledge plate for a traveling stoker.

It is an object of this invention to construct a ledge plate which is characterized by having spaced pads on the underside thereof for resting upon the top of the stoker side frame section to keep the plate slightly raised above the stoker frame for air circulation.

A further object of the invention is to provide the ledge plate with a depending narrow lip portion on the underside thereof which is adapted to be set very close to the ends of the carrier bars of the stoker traveling grate so that in the event of its rubbing on the ends of the bars, it would wear away without interfering with the stoker operation.

A further object of the invention is to provide the ledge plate with lug portions on the underside thereof adapted to project down over the top of the stoker side frame to prevent the ledge plate from working loose.

Still further, the invention contemplates constructing the ledge plate from a plurality of adjacent units and to arrange the units for directing air from the interior of the stoker to pass beneath and cool the units.

A further object of the invention is to arrange the ledge plate with the lip portion previously mentioned, formed with slots continuing into the body of the ledge plate to allow as much air as possible to cool the plate without weakening it.

Still further, the invention contemplates the provision of small end wall portions on the outer ends of the end units of the ledge plate continuing from the ends of said lip portions to the side frame section to close the opening under the frame and prevent air from blowing out the front of the stoker.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse sectional view of a portion of a traveling grate stoker equipped with a ledge plate according to this invention.

Fig. 2 is a perspective view of one of the end units of the ledge plate, illustrated bottom side up.

Fig. 3 is a fragmentary bottom view of the ledge plate showing several of the units.

The air cooled ledge plate, according to this invention, is used in conjunction with a traveling grate stoker having a stoker side frame section 5 adjacent a traveling grate 11. The grate 11 is moved by the conventional chain 12. Further details of the stoker will not be given in this specification as they form no part of the invention.

The ledge plate consists of a plurality of adjacent units, each unit comprising a body 14 having a flat top portion 15. Spaced pad portions 16 are formed on the underside of the body and are for the purpose of resting on the top of said frame section 10 to keep the frame slightly raised above the stoker side frame for air circulation. Furthermore, if desired, shims (not shown on the drawing) may be engaged beneath the pad 16 for properly mounting the ledge plate. 10

A depending narrow lip portion 17 is arranged on the underside of the said body 14 at the inner side thereof and is adapted to be set very close to the ends of the carrier bars of the stoker traveling grate 11 so that in the event it rubs against 25 the ends of the bars it would wear away without interfering with the stoker operation.

Lug portions 18 are arranged on the underside of the body 14 and are adapted to project down over the top of the stoker side frame and against 30 the outer edge of the frame to prevent the plate from working loose or moving. Furthermore, these lugs serve to keep the units in line with each other. The lugs 18 are reinforced with rib portions 19. These rib portions connect with edge 35 extension portions 20 from the outer edge of the body 14. The said lip portion 17 is formed with slots 21 extending into the body 14 for a short distance up to the points 21, to allow as much air as possible to cool the plate without weakening it. 40

A shoulder portion 22 is formed in the bottom of the body 14 opposed to the lug portions 18 and is adapted to engage against the inner edge of the side frame section 10 to assist in holding the ledge plate in position.

In Fig. 3 the ledge plate is shown to comprise several of the units. These units are broadly indicated by the letters A, B and C. The end units A and C have small end wall portions 24 on their outer ends continuing from the ends of the lip portions 17 and extending to the stoker side frame section 10 (see Fig. 1) to close the opening under the ledge plate and prevent air from blowing out to the front of the stoker. The ledge plate is extended along the entire length of 50 55

the stoker side frame 10 and between the walls 25 of the furnace.

- In operation of the device the forced air draft within the stoker compartment will pass beneath 5 the lip portions 17 and be confined beneath the ledge plate. Some of this air will continue through the slots 21 to cool the fire side of the ledge plate as much as possible. This air draft will also leak outwards and circulate beneath 10 the outer side of the ledge plate, that is, between the pad portions 16. Thus, the temperature of this ledge plate will be much lower than ledge plates not provided for the circulation of air. It consequently will last much longer.
- 15 An important feature of the invention resides in the construction of the narrow lip portion 17. This lip portion is very close to the ends of the carrier bars of the stoker traveling grate. Because it is narrow it will readily wear away in 20 the event that the bars of the grate engage against it, and will thus eliminate a possible breakdown of the stoker operation. Heretofore, the engagement of the bars of a stoker traveling grate against the ledge plate has been one of the 25 causes for the breakdown in operation of the stoker. The unburned fuel tends to build up in the ends of the grate bars and under the ledge plates, and if it does so accumulate, it will be wasted since it is then carried to the rear and dumped 30 into the ash pit. The thin lip portion 17 prevents the unburned fuel from accumulating by damping it off. This is instrumental in the saving of fuel. The thin lip portion 17 also prevents the fire from burning back gradually into the brick work and reaching the side frame of the stoker.
- 35 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I 45 claim as new, and desire to secure by United States Letters Patent is:—

1. In combination with a traveling grate stoker having a stoker side frame section adjacent a traveling grate, a base plate consisting of adjacent 50 units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close to the ends 55 of the carrier bars of the traveling grate of the stoker so that in the event of its rubbing on the ends of the bar it would wear away without interfering with the stoker operation, and lug portions on the underside of said body adapted to project down over the top edge of the stoker side frame to prevent the plate from working loose.

2. In combination with a traveling grate stoker 65 having a stoker side frame section adjacent a traveling grate, a base plate consisting of adjacent units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close to the ends 70 of the carrier bars of the traveling grate of the stoker so that in the event of its rubbing on the ends of the bar it would wear away without interfering with the stoker operation, lug portions on the underside of said body adapted to project down over the top edge of the stoker side frame to prevent the plate from working loose, and a shoulder portion on the bottom of said body and 75

rubbing on the ends of the bar it would wear away without interfering with the stoker operation, and lug portions on the underside of said body adapted to project down over the top edge of the stoker side frame to prevent the plate from working loose or moving, and also to keep the units in line with each other, said lip portion having slots continuing into said body to allow as much air as possible to cool the plate without weakening it.

3. In combination with a traveling grate stoker having a stoker side frame section adjacent a traveling grate, a base plate consisting of adjacent units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close to the ends of the carrier bars of the traveling grate of the stoker so that in the event of its rubbing on the ends of the bar it would wear away without interfering with the stoker operation, lug portions on the underside of said body adapted to project down over the top edge of the stoker side frame to prevent the plate from working loose, and end wall portions on the outer ends of the end units continuing from the ends of said lip portions to the side frame section to close the opening under the plate and prevent air from blowing out the front of the stoker.

4. In combination with a traveling grate stoker having a stoker side frame section adjacent a traveling grate, a base plate consisting of adjacent units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close to the ends of the carrier bars of the traveling grate of the stoker so that in the event of its rubbing on the ends of the bar it would wear away without interfering with the stoker operation, lug portions on the underside of said body adapted to project down over the top edge of the stoker side frame to prevent the plate from working loose, and end wall portions on the outer ends of the end units continuing from the ends of said lip portions to the side frame section to close the opening under the plate and prevent air from blowing out the front of the stoker, said lip portion having slots continuing into said body to allow as much air as possible to cool the plate without weakening it.

5. In combination with a traveling grate stoker having a stoker side frame section adjacent a traveling grate, a base plate consisting of adjacent units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close to the ends of the carrier bars of the traveling grate of the stoker so that in the event of its rubbing on the ends of the bar it would wear away without interfering with the stoker operation, lug portions on the underside of said body adapted to project down over the top edge of the stoker side frame to prevent the plate from working loose, and a shoulder portion on the bottom of said body and 75

opposed to said lug portions for engaging against the said side frame section to assist in holding the ledge plate.

6. In combination with a traveling grate stoker having a stoker side frame section adjacent a traveling grate, a base plate consisting of adjacent units, each unit comprising a body having a flat top portion, spaced pad portions on the underside thereof and resting on the top of said frame section to keep the plate slightly raised above the stoker side frame for air circulation, a depending narrow lip portion on the underside of said body which is adapted to be set very close

to the ends of the carrier bars of the traveling grate of the stoker so that in the event of its rubbing on the ends of the bar it would wear away without interfering with the stoker operation, lug portions on the underside of said body adapted to project down over the top edge of the stoker side frame to prevent the plate from working loose, edge extension portions on the outer side of the body immediately adjacent said lug portions, and reinforcing ribs from said extensions 10 to the lug portions. 5
